UNITED STATES PATENT OFFICE.

HAROLD G. MEAD, OF CHICAGO, ILLINOIS, ASSIGNOR TO CAR DUMPER & EQUIPMENT CO., OF CHICAGO, ILLINOIS, A CORPORATION OF ILLINOIS.

RECEIVING AND LOADING HOPPER.

Application filed March 6, 1925. Serial No. 13,523.

To all whom it may concern:

Be it known that I, HAROLD G. MEAD, a citizen of the United States, residing at Chicago, in the county of Cook and State 5 of Illinois, have invented a new and useful Improvement in Receiving and Loading Hoppers, of which the following is a specification.

This invention relates to improvements 10 in hoppers, and more especially to a hopper adapted for use in connection with continuous loading as practiced, for example, in mining.

In my co-pending application (Serial 15 Number 13,522 of even date herewith) covering inventions in the art of mining, I have shown and described a method of mining making use, in general, of a loading machine placed in a room at the face of 20 the material adapted to pick up the shot material and deliver the same in a continuous stream into a proper receptacle. The receptacle there shown comprises what I have termed a receiving and loading hopper. 25 From this hopper, a shuttle car takes loads intermittently and carries them to the stub entry or room entry where the shuttle car is unloaded by a shuttle car unloader and the contents dumped into the mine cars 30 operating in the cross entry. The hopper described and claimed in this application may be termed a receiving and loading hopper and is so designed that it is especially adapted for use in the method of 35 mining described in said co-pending application. It is obvious, however, that it may be used in other ways and for other purposes, without detracting from the spirit of this invention.

40 In that form of device embodying the features of my invention shown in the accompanying drawings, Figure 1 is a vertical sectional view of the improved hopper, Fig. 2 is a view taken as indicated by the line 2 of Fig. 1, and Fig. 3 is a view taken as indicated by the line 3 of Fig. 1.

45 As shown in the drawings, 10 indicates the hopper which is supported in any suitable manner as for example by the legs 11, 11. The hopper is held a sufficient distance above the floor in order to permit a car 12 to go under the same. The car 12 here shown may, for example, be the shuttle car spoken of in my co-pending application

above referred to covering a continuous 55 loading method of mining.

The shuttle car 12 is adapted to go under the hopper 10 from the right hand side (as viewed in Fig. 1) moving to the left until it is exactly under the hopper as shown in 60 Fig. 1. In leaving the hopper the car moves to the right (as viewed in Fig. 1). The end of the hopper at which the shuttle car enters and leaves, that is the right hand end (as viewed in Fig. 1) I will designate 65 as the front of the hopper.

The rear half of the bottom of the hopper is formed by a stationary plate or bottom section 14; and the front half comprises two sliding plates or bottom sections 15, 70 15, one operating on each side of a centrally arranged longitudinal bottom supporting strip 13 and adapted to slide between the channel members 16, 16. Since the construction and operation of each of the sliding 75 sections 15 is the same, I will describe in detail but one.

The sliding section 15 is adapted to slide under the stationary section 14. Near the front edge of the section 15 on the under 80 side there is provided a downwardly projecting lug 17. In front of the lug 17 is a pair of shorter lugs 18, 18. Arranged between the lugs 18 is a vertically movable 85 latch member comprising an inverted U-shaped piece 19 projecting through a hole 19^a in the plate 15 and carrying at its lower end a beveled latch 20. At the front of the hopper on the under side is mounted a wedge-shaped member 21 adapted to go 90 through the U-shaped piece 19 and raise the same upon forward movement of the bottom section 15.

The operation of the device is as follows. 95 When the shuttle car 12 is not under the hopper, the bottom of the hopper is closed. That is, the two sliding sections 15 are both to the right as far as they will go, thus forming a complete closure for the bottom with the stationary section 14. As the 100 shuttle car 12 starts to go under the hopper, the upper edge of its front side 22 engages the lugs 17 on the sliding sections 15. Further movement of the shuttle car 12 slides these sections to the left, thus permitting 105 material to flow from the hopper into the shuttle car 12. As the sections 15 move to the left, the members 19 ride down off of

the wedges 21 thus permitting the latches 20 to drop into place, as shown in Fig. 1, on the right hand side of the upper edge of the front face 22 of the car. As the car 5 12 moves to the right to leave the hopper, the upper edge of the face 22 engages with the latches 20, to draw the sections 15 into closed position. As they reach the entirely closed position, the U-shaped members 19 10 ride up on the wedges 21 thus lifting the latch members 20 to permit the car to leave the hopper. It will be seen, therefore, that the shuttle car 12 in thus going under the hopper opens the bottom to receive a load of material and in leaving the hopper again, 15 closes the bottom to prevent material from falling out on the floor.

While I have shown and described certain embodiments of my invention, it is to 20 be understood that it is capable of many modifications. Changes, therefore, in the construction and arrangement may be made without departing from the spirit and scope of the invention as disclosed in the appended claims, in which it is my intention 25 to claim all novelty inherent in my invention as broadly as possible in view of the prior art.

It is to be noted that the hopper is supported on the legs 11; and that these legs may be removed or folded up out of the way. The apparatus is so constructed that the hopper can be carried from place to place on the car. This is easily accomplished by removing or folding the legs 11 out of the way thus allowing the hopper to rest on the car and be carried thereby.

What I claim as new, and desire to secure by Letters Patent, is:

40 1. A hopper adapted to receive a continuous supply of material; a car adapted to receive a load of material from the hopper; means for supporting the hopper a sufficient distance above the floor to permit the car 45 to go under the same; means operated by movement of the car to a position under the hopper to open the hopper and discharge a load of material into the car; means operated by movement of the car in leaving a 50 position under the hopper to close said hopper and prevent further discharge of material therefrom; and means whereby the hopper can be carried on the car.

55 2. A hopper adapted to receive a continuous supply of material; a car adapted to receive a load of material from the hopper; means for supporting the hopper a sufficient distance above the floor to permit the car to go under the same; a sliding bottom 60 section in the hopper; a part on said bottom section adapted to be engaged by a part on the car whereby said bottom section is slid to an open position by movement of said car to a position under said hopper; a part on 65 said bottom section adapted to be engaged

by said car whereby said bottom section is moved to closed position upon movement of said car in leaving its position under said hopper; and means whereby the hopper can be carried on the car.

70 3. A hopper adapted to receive a continuous supply of material; a car adapted to receive a load of material from the hopper; means for supporting the hopper a sufficient distance above the floor to permit the car to go under the same; a sliding bottom section in the hopper; a part on said bottom section adapted to be engaged by a part on the car whereby said bottom section is slid to an open position by movement of said car to a position under said hopper; a latch member on said bottom section adapted to be engaged by said car whereby said bottom section is moved to closed position upon movement of said car in leaving its position under said hopper; means whereby said last mentioned parts are disengaged upon the bottom section reaching its closed position; and means whereby the hopper can be carried on the car.

75 4. A hopper adapted to receive a continuous supply of material; a car adapted to receive a load of material from the hopper; means for supporting the hopper a sufficient distance above the floor to permit the car to go under the same; a sliding bottom section in the hopper; a part on said bottom section adapted to be engaged by a part on the car whereby said bottom section is slid to an open position by movement of said car to a position under said hopper; a latch member on said bottom section adapted to be engaged by said car whereby said bottom section is moved to closed position upon movement of said car in leaving its position under said hopper; means whereby said last mentioned parts are disengaged upon the bottom section reaching its closed position; and means whereby the hopper can be carried on the car.

80 5. A hopper adapted to receive a continuous supply of material; a car adapted to receive a load of material from the hopper; means for supporting the hopper a sufficient distance above the floor to permit the car to go under the same; a sliding bottom section in the hopper; a part at or near the forward edge of said bottom section adapted to be engaged by a part on the car whereby said bottom section is slid to an open position by movement of said car to a position under said hopper; a part on said bottom section adapted to be engaged by said car whereby said bottom section is moved to closed position upon movement of said car.

car in leaving its position under said hopper; and means whereby the hopper can be carried on the car.

6. A hopper adapted to receive a continuous supply of material; a car adapted to receive a load of material from the hopper; means for supporting the hopper a sufficient distance above the floor to permit the car to go under the same; a sliding bottom section in the hopper; a part at or near the forward edge of said bottom section adapted to be engaged by a part at or near the forward end of the car whereby said bot-

tom section is slid to an open position by movement of said car to a position under said hopper; a part on said bottom section adapted to be engaged by said car whereby said bottom section is moved to closed position upon movement of said car in leaving its position under said hopper; and means whereby the hopper can be carried on the car. 15 20

Witness my hand and seal this 28 day of February, A. D. 1925.

HAROLD G. MEAD. [L. S.]
